UNITED STATES PATENT OFFICE.

VIRGIL DRAPER, OF NORTH ATTLEBOROUGH, ASSIGNOR TO OSCAR M.
DRAPER, OF BRISTOL, MASSACHUSETTS.

DESIGN FOR AN ORNAMENTAL CHAIN-LINK.

Specification forming part of Design No. 6,781, dated July 22, 1873; application filed May 24, 1873.

A.

To all whom it may concern:

Be it known that I, VIRGIL DRAPER, of North Attleborough, in the county of Bristol and State of Massachusetts, have invented a new and Improved Design for Ornamental Chain-Links; and I do hereby declare that the following specification, taken in connection with the drawing making a part of the same, is a full, clear, and exact description thereof.

The design for a chain-link exhibited in the drawing is formed by a link proper, *a*, which has open ends for the insertion of rings to connect the link with the next one in the chain. Midway between the ends of the link

is inserted a bar, *b*, whose axis is at right angles with the longitudinal axis of the link. The link *a* and the central member *b* are combined by means of a fillet, *c*.

What I claim as new, and desire to secure by Letters Patent, is—

1. The design for an ornamental chain-link, herein described and shown.
2. The design for an ornamental chain, herein described and shown in Figure 3 of the drawing.

VIRGIL DRAPER.
